C. J. FAY, OF HAMMONTON, NEW JERSEY.

Letters Patent No. 60,708, dated January 1, 1867.

IMPROVEMENT IN ROOFING AND SIDING FOR HOUSES.

The Schedule referred to in these Letters Patent and making part of the same.

TO ALL WHOM IT MAY CONCERN:

Be it known that I, C. J. FAY, of Hammonton, in the county of Atlantic, and State of New Jersey, have invented a new and improved Roofing and Siding or covering for buildings, cars, decks of vessels, awnings, carriages, &c.; and I do hereby declare that the following is a full, clear, and exact description thereof, which will enable others skilled in the art to make and use the same.

The present invention relates to the use of paper made of manilla, hemp, or grass, according to the process and mode described and embraced in the specification accompanying the application for Letters Patent made by T. IRVING, J. McNEIL, GEORGE W. RICH, and CYRUS J. FAY, as inventors, to the United States Patent Office, for the purpose of a roofing and siding for buildings, and as a covering or roofing for the tops and sides of cars, decks of vessels, and carriages, either upon the inside or outside of the same, or both, and for the purpose of awnings or shades, or for any other purpose where it is desired to render the surface on which the said paper is used water-proof, or, in other words, impervious to moisture or the air; as, for instance, as a lining to sinks, tubs, and other receptacles for water or other liquids which will not affect the texture of the said paper, or as a carpet or covering for the floors of rooms, or as a substitute for the ordinary plaster ceilings of rooms; the said paper, when used as a roofing or siding or covering for buildings, &c., being applied in an extremely novel and in such a manner as will be presently explained, that the nails, tacks, or other devices used as a means of fastening it thereto will not be exposed to the action of the atmospheric elements, but will be completely covered or encased, as it were, by the paper itself, whereby their preservation is secured.

In order to render the explanation of the mode of securing the paper above referred to, to the sides and roofs of houses or other buildings or other structures more intelligible and distinct, reference is had to the accompanying plate of drawings, in which—

Figure 1 is a view of one end of a house covered with the said paper according to the mode which is to be hereinafter described.

Figure 2, a sectional detail view of a portion of the building illustrated in fig. 1, but on a somewhat enlarged scale; and

Figure 3, a surface view of the paper as prepared for being used as a roofing or siding to buildings.

Similar letters of reference indicate like parts.

In the application and use of the paper, which is embraced in the application for Letters Patent hereinbefore referred to, to the roofs and sides of houses or other buildings, I deem it best, during the process of manufacture, to make or run it into strips or sheets, say of about three (3) feet, more or less, in width, and of any desired but convenient length for use; which strips or sheets of paper I then cause, either while the paper is being made or by passing it afterwards through a separate machine suitable therefor, to be marked or creased across its width and at regular points of its length with parallel lines in groups of three each, with an inch or more or less space between the several lines of each group of lines, and with a space equal to the width of the siding desired; as, for instance, four or five inches, or more or less, between each and all the several groups of lines or creases, together with a series of dots or small spots, or their equivalents, in the space embraced between every two of the lines or creases of each and all the several groups of the same, corresponding in position with each other, throughout the whole length of the paper sheet or strip; these dots being made at equal and regular distances apart, or from each other, and being provided for indicating the points of the paper where the nails, tacks, or similar fastening devices should be inserted and driven through it when applied to the roof or sides of a building in the manner to be now explained.

To apply the paper sheets or strips prepared in the manner above stated to the sides and roofs of a house, for instance, I first cut the said strips into such lengths as will be sufficient for covering the entire length or extent of surface to which it is to be applied; when, taking one of such strips so cut by one of its ends, I secure it to the point or part of the outside of the house at which it is desired or deemed best to commence, by means of nails or other simple fastening devices, which I drive through it at the points as dotted or spotted; after which I fold the paper along such one of its creases or lines, of the group of lines in which such dots or spots are indicated, and in such a manner as to be over or cover the heads of the said nails, &c., when from such folded edge I continue to lay the paper upon the surface which is to be covered by it until coming to the

next group of lines or creases. I then so fold such portion of the paper as is embraced between the width of the several lines of such group, over and upon itself, as to bring the dotted space of the said group over and upon the space not dotted, when, there securing the paper by driving through it at the points indicated by the dots or spots, the fastening tacks, &c., used, I proceed to again fold the paper over the heads of such tacks, and to lay and again fold it, and so on until the entire length of the paper is exhausted or the whole extent of the surface is covered by it in a similar manner to that just above described. To cover the entire extent or surface of the sides or roof, or both, of buildings, it is only necessary to proceed in a similar manner to that above stated for each successive sheet or strip of paper used; care being taken, of course, to nicely joint the several strips together at their sides or ends, and to cover them, as is now the case with the ordinary wooden siding, &c., by the usual trimming boards or strips applied to the corners, &c., of houses and other buildings; these portions of the operations being similar to that now in common use and practice in the erection of buildings that are covered with wooden siding, &c., and therefore needing no particular explanation herein, as it forms no part of the present invention.

Thus, from the above description, it is plainly obvious that by the manner of laying the paper the fastening nails used are entirely covered or encased by the paper, and consequently are thereby protected from the action of the atmospheric elements, the importance of which is obvious.

After a house has been roofed and sided with paper in the manner above explained, paint, tar, or other suitable medium may be applied to the paper to protect it or beautify its appearance, as in the case of the ordinary wooden or other siding or roofing.

It is hardly necessary for me herein to specify any of the many advantages secured by my invention, as, from the well-known property of paper as a non-conductor of heat and cold, it for that reason alone, if for no other, would be the most desirable covering for the exterior of buildings, provided the paper is rendered impenetrable or impervious to moisture and air; and as this property is secured in the paper manufactured under and by the mode or process hereinbefore referred to, it is plainly obvious that this difficulty heretofore in the way of the use of paper as a roofing or siding has been at last overcome; a result or desideratum of the utmost importance.

And in addition to the above it may be here observed that paper is one of the cheapest materials which can be used for roofing or siding or for a covering to any surface; and that the mode of applying it herein above particularly explained is not only in itself cheap, but simple, quick, efficient, and practical to the utmost degree or extent.

I claim as new, and desire to secure by Letters Patent—

The use of, and the manner of applying, paper for roofing and clap-boarding, substantially as described.

C. J. FAY.
